UNITED STATES PATENT OFFICE.

PAUL MAUSER, OF OBERNDORF-ON-THE-NECKAR, WÜRTEMBERG, GERMANY.

MACHINE FOR RIFLING GUN AND PISTOL BARRELS.

SPECIFICATION forming part of Letters Patent No. 259,031, dated June 6, 1882.

Application filed December 27, 1881. (No model.) Patented in Germany November 14, 1881.

To all whom it may concern:

Be it known that I, PAUL MAUSER, of Oberndorf-on-the-Neckar, Kingdom of Würtemberg, Germany, have invented certain new and useful Improvements in Machinery for Rifling the Barrels of Guns, Pistols, &c., of which the following is a specification.

The invention will be understood as set forth and claimed herein.

10 The accompanying drawings form a part of this specification and illustrate the invention. Figure 1 is a front elevation, showing the essential parts of the device. Some of the parts are broken away to show others back of them. Fig. 2 is an end view, looking in the direction of the arrow in Fig. 1. Fig. 3 is a plan view of the device. Fig. 3^a is a detail of the outer end of the ruler and the link in which it may be adjusted. Fig. 4 shows a top and front 15 view of the guide. Fig. 5 is a vertical section of Fig. 2. Fig. 6 is a horizontal section of the device, taken through the rear bolt of the ruler. Fig. 7 shows a top view and horizontal section of the guide and pin-slide. Fig. 8 is a front 20 view of the guide, having the slot-carrying portion adjustable. Fig. 9 is a vertical section of Fig. 8. Fig. 10 is a horizontal section of the same, taken through the slot. Fig. 11 shows a modified form of the means for elevating or 25 depressing the ruler. Fig. 12 is a vertical section through the rear bolt of the form shown in Fig. 11.

Similar letters of reference indicate corresponding parts in all the figures.

30 A is the ruler, and B the front link, up and down in which the ruler, is adjustable. A way or race is provided in the ruler in which the cutter-head carrying the cutting-tool works. These parts are common to all machines of 35 this class, and I have not deemed it necessary to illustrate the cutter-head and cutting-tool. The inclined position of the ruler A, as is well known in the art, causes the tool to cut a uniform screw-line in the gun-barrel. By means 40 of the adjustability afforded by the link B the twist of the cuts may be made smaller or larger; but during the rifling the ruler A has hitherto been kept stationary. To produce the tapering cut, which is the object of this invention, 45 the ruler is moved. To accomplish this the ruler A is raised and lowered uniformly and

automatically by the mechanism about to be described. The outer end of the ruler A is pivoted to a bolt which passes through the link B. The inner end is forked and straddles the block b, which turns on a bolt, a, fixed to the lower end of an upright guide, D. The guide D moves up and down in ways on a fixed bracket, E. A piece of hard metal, c, is placed in the upper part of the guide D, and is provided with a slot, c', set in an inclined position in the piece c. A horizontal slide, e, moved in ways in the bracket F, is provided with a pin, d, which works in the slot c' and produces a reciprocating movement of the guide D as the slide e is moved back and forth. A bar, H, mounted in bearings g on the plate G, and actuated by a cam on the main shaft of the machine, (not shown,) carries the tappets f f', which ship the slide e back and forth. The inner end of the ruler A is thus elevated or depressed by the action of the tappets f f' on the slide e operating upon the guide D by means of the pin d and slot c'.

Suppose the cutting-head to be making its back-stroke—that is, traveling from the muzzle to the breech of the barrel—and the ruler A to be in its elevated position, the cut will be of uniform twist, as the position of the ruler is not changed during the stroke. After the 75 cutter leaves the barrel it travels about one and one-half inch farther. During this time the front tappet, f, strikes the slide e, forces it back, and thus lowers the inner end of the ruler A, and the cutting-head is thereby turned 80 slightly. While the cut is being made in the reverse way (from the breech to the muzzle) the twist of the cut is shorter or narrowed, and gradually the two cuts run into each other toward the muzzle, so that the cut at the breech, 85 where the width of the two cuts lies side by side, will be much broader than at the muzzle, where they merge into each other. The two cuts taken together make one tapering one, narrower at the muzzle and broader at the breech. 90 When the forward rifling is done—i. e., the cutting from the breech to the muzzle—and while the cutting-tool is playing over the one and a half travel outside the end of the barrel, the tappet f ships the slide e, and the cutting-head is turned to the position it first occupied. 95 In the completed form of the invention the

metal piece *e*, with the inclined slot *c'*, is made so as to be capable of adjustment and change of inclination, so that the elevation and depression of the ruler *A* will be greater or less. 5 This form is shown in Figs. 8, 9, and 10. The piece *e* is here made a circular plate toothed upon its circumference. A worm, *h*, supported in bearings in the side of the guide *D*, engages with the teeth on the piece *e*. By turning the worm the piece *e* is revolved and the inclination of the slot *c'* is changed, so that the end of the ruler *A* will be raised or lowered to a greater or less extent.

10 The modification shown in Figs. 11 and 12 shows the ruler *A* raised or lowered by resting on the wrist-pin *i*, which is set eccentric to the bolt *a*. The part *D* is formed into a forked lever embracing at its bifurcated end the bar *H*, and is operated directly by the tappets *ff'*.

15 At the lower end of the lever the bolt *a* is secured to it and turned by it. The motion of this lever *D* is limited by a stop, *k*, working in a slot near the base. In this form the tappets *ff'*, and also the stop *k*, are made adjustable. 20 Hence this device will answer all the purposes of the adjustable form shown in Figs. 8, 9, and 10.

The device in any of its forms may be applied to an old rifling-machine of any form, as well as incorporated in a new machine. 30

Having thus described my invention, what I claim is—

1. The combination, with the ruler *A*, in which the cutter-head is held, of an automatically-operated elevating and depressing means, 35 *D*, attached thereto, whereby one end of the ruler is elevated or depressed, substantially as set forth.

2. The combination of the ruler *A* and guide *D*, provided with the slot *c'*, of the slide *e*, pin *d*, and tappets *ff'*, operated from the main shaft of the rifling-machine, substantially as set forth. 40

3. The combination, with the piece *e*, having the slot *c'* and adjusting means *h*, of the guide *D*, ruler *A*, and operating means, substantially as set forth. 45

This specification signed by me this 25th day of November, 1881.

PAUL MAUSER.
